United States Patent Office

Des. 198,541
Patented June 30, 1964

198,541

LIGHT LENS

Seymour Sohn, 842 Jacon Way, Pacific Palisades, Calif.

Filed Oct. 23, 1962, Ser. No. 72,240

Term of patent 14 years

(Cl. D48—32)

FIG. 1.

FIG. 2.

FIG. 3.

FIG. 4.

FIGURE 1 is a front elevational view of a light lens showing my new design;

FIGURE 2 is a side elevational view thereof;

FIGURE 3 is a rear elevational view thereof; and,

FIGURE 4 is a cross section as taken in the direction of the arrows 4—4 of FIGURE 1.

I claim:

The ornamental design for a light lens, substantially as shown.
